(57) **CLAIM**

The ornamental design for a nursing bra, as shown and described.

DESCRIPTION

FIG. 1 is a perspective view taken from the front and left side showing one representation of the design;

FIG. 2 is a front elevational view of the design shown in FIG. 1;

FIG. 3 is a side elevational view of the design shown in FIG. 1;

FIG. 4 is a rear elevational view of the design shown in FIG. 1; and,

FIG. 5 is a perspective view from the front and left side showing a representation of the design shown in FIG. 1 in an open position.

The broken line partially showing a human torso in FIGS. 1 and 5 illustrate the portion of the design that forms no part of the claim. The broken lines shown on the surface of the claimed design throughout the views, represent stitching.

1 Claim, 4 Drawing Sheets

FIG. 3.

FIG. 4.

FIG. 5.
